SYSTEM FOR WEATHER-STRIPPING
SLIDING SASH WINDOWS

Daniel Pettigrew Robertson, Arlington, Va.

Application January 4, 1943, Serial No. 471,287

3 Claims.

(Cl. 20—69)

This invention relates to a system for weather stripping a sliding sash window.

One of the objects of the invention is to provide a transverse weather stripping at the top and bottom of the window, carried respectively by the bottom rail of the lower sash flush with the inner surface thereof and by the top rail of the upper sash flush with the outer surface thereof, contacting respectively the horizontal surfaces of the bottom and top window frame members.

Another object of the invention is the provision of lateral weather stripping secured to the nose of the parting bead throughout its length, having a linear yielding packing element projecting oppositely from its respective lower and upper portions, contacting respectively the adjacent outer face of the side rail of the lower sash and the adjacent inner face of the side rail of the upper sash.

A further object of the invention is to provide the lateral weather stripping with a resilient stop at the height of the meeting rails constituting a transverse continuation of the longitudinal weather strips between the sides of the lower and upper sashes and the window frame, and also functioning as a localized guiding means for the lower sash.

Still another object of the invention is the provision of a weather strip on the under side of the meeting rail of the upper sash projecting across the joint between the meeting rails of both sashes.

Another object of the invention is the correlation of the structures referred to in the above objects, providing a complete weather seal for a window of the type described.

Other objects of the invention will appear as the following description of a preferred and practical embodiment thereof proceeds.

In the drawing which accompanies and forms a part of the following specification and throughout the several figures of which the same characters of reference have been employed to denote identical parts:

Figure 1 is a front view in elevation of a window, weather stripped in accordance with the principles of the invention;

Figure 2 is a cross-section, part being broken away, taken along the line 2—2 of Figure 1;

Figure 3 is a cross-section, part being broken away, taken along the line 3—3 of Figure 1;

Figure 4 is a cross-section, part being broken away, taken along the line 4—4 of Figure 1;

Figure 5 is a perspective view illustrating in

particular the transverse stop at the ends of the meeting rails;

Figure 6 is a perspective view in detail showing the transverse stop in operative relation to the meeting rails;

Figure 7 is a perspective view of a detail of construction illustrating the construction and arrangement of the weather strip at the bottom of the lower sash.

Referring now in detail to the several figures, the weather strip preferably employed in carrying out the subject invention is of the type perhaps best shown in Figure 5, consisting of a wooden batten 1 having a rabbet 2 on its under side and a length of flexible wicking 3 seated in the rabbet and secured thereto as by stapling, the wick being flush with the under side of the batten 1 and having a margin 4 projecting beyond one longitudinal edge of the batten.

The invention contemplates the application of this type of weather strip to completely seal the air leakage path between the two sliding surfaces 5 and 6 and the window frame 7, and between the meeting rails 8 and 9 of said sashes, with the additional intercalation of the stop 10 across the gap at the ends of the meeting rails 8 and 9 of the sashes.

In applying the weather strip to the bottom and top rails 11 and 12 of the respective lower and upper sashes, the lower inner edge of the rail 11 and the upper outer edge of the rail 12 are rabbeted and lengths of weather strip 15 and 16 are set into the respective rabbets for the full length thereof and nailed in place, the wick 14 projecting downwardly below the rail 11 and upwardly above the rail 12, the wick being trained so that its side makes contact with the sill 13 of the window frame, in the case of the lower sash rail 11, and its side makes contact with the top frame member 14 in the case of the upper sash rail 12. As the wick, thus trained, is resilient, it engages the window frame with yielding pressure, thus forming an effective seal.

Particularly with respect to the lower sash, the interposition of the wick margin between the rail 11 and sills 13 spaces these parts a slight distance apart, preventing the retention of moisture which would tend to rot said parts, and in the case of freezing, would cause the lower sash to become stuck in closed position.

In sealing the crack between the meeting rails 8 and 9, a length of weather strip 12" is nailed to the under side of the meeting rail 9 of the upper sash toward the inner side thereof with the

wicking adjacent the rail, having its projecting marginal portion extending beneath the joint between the meeting rails. Said projecting portion presses yieldingly against the under side of the meeting rail 8, making an effective seal.

The leakage path between the sides of the sashes and the window frame is sealed on each side by nailing the weather strip to the nose of the parting bead 17 between the sashes for the full length of said parting bead. The weather strip is divided into two sections 18 and 19, the line of division being intermediate the planes of the top and bottom faces of the meeting rails when the sashes are closed. The wicks are in reversed relation, the projecting wicking of the lower section being in the path of the lower sash, while the projecting wicking of the upper section is in the path of movement of the upper sash. The wicking is trained to lie flatwise against the edge so that it presses resiliently there- 20 against.

If the partition bead is bull-nosed, it may be removed and planed flat preparatory to the installation of the weather strip, but it is preferably substituted by a flat-nosed parting bead.

It still remains to seal the leakage path upward past the ends of the meeting rails 8 and 9. This is accomplished by means of the stop 10, which is mounted on the weather stripping carried by the parting bead, overlying the junction between the wicks and located, when the sashes are closed, back of the ends of the meeting rail 8 of the lower sash and back of so much of the meeting rail 9 of the upper sash as extends forwardly of the plane of the inner faces of the side members of the upper sash.

The stop 10 is a resilient metal clip 21 having a securing lug 20 adapted to be nailed to the weather strip on the parting bead, and offset with respect to said lug to form a face 20' biased toward the sash, and engageable with the end of the meeting rail 8 with resilient pressure.

The upper end of the metal clip is overturned toward the parting bead, defining an enclosure which houses a short piece of weather strip 22, both the wood and wick element with the wick element 23 projecting outwardly toward the upper sash. In order to make room for the stop 10, the end of the meeting rail 8 of the lower sash is cut sufficiently shorter in a vertical plane parallel to the end of said meeting rail, and the portion of the meeting rail 9 which projects inwardly beyond the plane of the inner faces of the sides of the upper sash is likewise cut away to make room for the projecting wick portion 23 of the weather strip 22. The metal clip 21 extends just to the upper outer edge of the meeting rail 8 and the projecting wick portion 23 contacting the back of the rabbet formed by cutting off the inwardly projecting portion of the end of the meeting rail 9.

The lower sash 5 makes the usual free fit with the sides of the window while being raised or lowered, until it is lowered to the point at which the meeting rail 8 encounters the stops 10. When this position has been reached, the stops 10 exer-

cise a localized friction against the ends of the meeting rail 8, due to the outward pressure of the metal clip 21 which also hold the sash against rattling when the sash is closed.

It will be understood to those skilled in the art that by the construction and installation of the weather stripping as above described, a complete barrier has been interposed to weather leakage from the outside to the inside about and between the sashes, and while I have specified certain preferred materials in the construction of the weather strip, these may be substituted by materials having an equivalent function without transcending the scope of the invention.

What I claim as my invention is:

1. System of weather stripping a sliding sash window of the conventional type having a frame, upper and lower sashes with meeting rails, and parting beads between the sashes, said system employing linear weatherstrip in the form of a rabbeted batten having a flexible element secured in the rabbet flush with a side of the batten and having a marginal portion projecting along a longitudinal edge of said batten, said system comprising a weather strip secured to a nose of the parting bead on each side of the window for the length of said parting bead, divided into two sections abutting at the level of the meeting rails, the upper section having the flexible margin pressing the inner side of the upper sash and the lower section having the flexible margin pressing the outer side of the lower sash with means bridging said sections at their abutting ends bearing against the meeting sash rails when the sash are closed.

2. System of weather stripping as claimed in claim 1, the flexible margins being trained to press sidewise against the respective sashes.

3. System of weather stripping a sliding sash window of the conventional type having a frame, upper and lower sashes with meeting rails, and parting beads between the sashes, said system employing linear weather strip in the form of a rabbeted batten having a flexible element secured in the rabbet flush with a side of the batten and having a marginal portion projecting along a longitudinal edge of said batten, said system comprising a weather strip secured to a nose of the parting bead on each side of the window for the length of said parting bead, divided into two sections abutting at the level of the meeting rails, the upper section having the flexible margin pressing the inner side of the upper sash and the lower section having the flexible margin pressing the outer side of the lower sash, and a stop secured to said weather strip overlying the joint between said sections, comprising a resilient clip biased toward the end of the meeting rail of the lower sash and engaging said meeting rail when the lower sash is closed; said stop extending the width of the parting bead and having a flexible element projecting from one side of said clip toward the upper sash, engaging the latter in the plane of the inner face of the side margins of said sash.

DANIEL PETTIGREW ROBERTSON.
